UNITED STATES PATENT OFFICE.

THOMAS H. KANE AND ALFRED J. URTUBEES, OF MILWAUKEE, WISCONSIN.

STEP-COVER FOR RAILWAY-COACH VESTIBULES.

No. 899,540.

Specification of Letters Patent.

Patented Sept. 29, 1908.

Application filed December 11, 1905. Serial No. 291,277.

To all whom it may concern:

Be it known that we, THOMAS H. KANE and ALFRED J. URTUBEES, citizens of the United States, and residents of Milwaukee, in 5 the county of Milwaukee and State of Wisconsin, have invented certain new and useful Improvements in Step-Covers for Railway-Coach Vestibules; and we do hereby declare that the following is a full, clear, and exact 10 description thereof.

Our invention relates to sliding step-covers in connection with swinging vestibule doors of railway-coaches, and has for its object to simplify and cheapen construction as well as 15 insure perfect working of said covers under all ordinary conditions; said invention consisting in what is hereinafter particularly set forth with reference to the accompanying drawings and pointed out in the claims, 20 especial attention being directed to the peculiar novel connection of the vestibule door and step-cover herein shown.

Figure 1 of the drawings represents an end elevation of a fragment of a railway-coach 25 vestibule and an application of our invention, this view being partly in section on the planes indicated by lines 1—1 in Fig. 3; Fig. 2, a side elevation of what is shown in Fig. 1, partly in section on the plane indicated by line 2—2 in the same figure, and Fig. 3, a plan view of said fragment of the railway-coach inverted and in horizontal section on the plane indicated by lines 3—3 in Fig. 1.

35 Referring by letter to the drawings, A indicates the platform of a railway-coach vestibule, B the steps and C a hinged outer door of the vestibule that is ordinarily closed and locked when the coach is moving as part of 40 a railway train. The usual steps B to the platform are shown, and the step-well is closed from the outside by the door C, the bottom of same in closed position being below the vestibule platform.

45 Various means have been devised to open and close the step-well relatively with the opening or closing of the vestibule-door, and it is old in the art to employ a sliding step-cover in connection with such a door to be 50 actuated by the same, but heretofore the connection of the two has been such as to

necessitate a slide block or roller in an under-side channel-bar or slot of the step-cover, the same being complicated, expensive and not satisfactory under all conditions to which 55 vestibuled railway-coaches are subjected.

In carrying out our invention we provide crossbeams of the coach-body with parallel angle-iron strips D, that extend parallel to the aforesaid platform directly under the 60 same and the whole width of the step-well to constitute supporting guides for a sliding step-cover E that is connected by a link F with the aforesaid door. One end of the link is pivoted on a stud a, at a fixed point of the 65 underside of the step-cover E and said link extends diagonally across said step-cover when the door C is closed. The other end of the link is pivotally connected to a bracket b mortised in the outer or swing edge of the 70 door, and said door being swung inward to open the vestibule, the step-cover is pushed back by the link F under the platform A, said door, link and step-cover being then alined 75 transversely of the coach.

From the foregoing it will be understood 75 that when the door C is closed the step-cover is drawn snug against the depending portion of said door to shut out weather and dust, while at the same time the pivotal connection of the link F at a fixed point of the step-cover simplifies and cheapens the mechanism for the operation of said step-cover by said door and insures of this operation under all 80 the various conditions to which the coach is 85 liable to be subjected.

We claim:

1. In a railway-coach having a vestibule and provided with guides extending under the vestibule-platform, the combination of a 90 sliding step-cover supported by the guides, a swinging vestibule-door, and a link in pivotal connection with the underside of the step-cover at a fixed point and likewise connected to the door, the link being diagonally of said 95 step-cover when said door is closed but alined therewith and the door when the latter is open.

2. In a railway-coach having a vestibule and provided with guides extending under the vestibule-platform, a sliding step-cover 100 supported by the guides, a swinging vestibule

door, a bracket mortised in the swinging edge of the vestibule-door, and a link in pivotal connection at its ends with the bracket and the underside of the step-cover at a

5 fixed point.

In testimony that we claim the foregoing we have hereunto set our hands at Milwaukee

in the county of Milwaukee and State of Wisconsin in the presence of two witnesses.

THOMAS H. KANE.
ALFRED J. URTUBEES.
